CONTROL FOR CIGAR MACHINE SHORT
FILLER TOBACCO FEEDS

Sigurd Clausen, Brooklyn, N. Y., assignor to International Cigar Machinery Company, a corporation of New Jersey

Application December 10, 1943, Serial No. 513,701

20 Claims. (Cl. 131—22)

1

This invention relates to mechanism for feeding tobacco to cigar machines and more particularly to improvements in devices for controlling the feed of measured quantities of tobacco in order that a substantially constant quantity of tobacco may always be available in a cigar bunch machine for forming substantially uniform bunch charges therefrom for delivery to the bunch rolling mechanism thereof.

In some machines, now in use, it is customary to form a column of tobacco to which additions are made cyclically during the operation of the machine but occasionally due to the presence of an excess of tobacco over that required for the formation of one or more bunches, the feeding operation is interrupted for one or more cycles until it is again necessary to add to quantity in the machine in order to maintain it in a predetermined condition with respect to quantity and density.

According to my invention there is provided an arrangement for automatically varying the amount of tobacco fed to a scale pan or weighing device in accordance with the quantity of tobacco remaining in a confining space after a charge has been removed therefrom. Thus, if the device which engages such quantity of tobacco or if some other detecting device finds a larger surplus available, the control mechanism of the invention will automatically control the next feeding operation of the tobacco feed correspondingly by varying the weighing effect of the scale pan. In other words the quantity of tobacco fed will vary in accordance with the amount of tobacco remaining in the confining mechanism, such as a charge compression chamber, in columnar form so that at substantially all times the quantity of tobacco cyclically available for separation of a bunch charge therefrom will be substantially constant.

It is an object of my invention to provide improved mechanism for forming cigar bunch charges by providing mechanism for maintaining a substantially constant quantity of tobacco available for bunch charge formation by controlling the amount of tobacco added cyclically to the quantity remaining after each charge formation.

It is a further object of my invention to provide improved weighing mechanism for weighing measured quantities of tobacco and automatically vary the capacity of the weighing device forming a part of this mechanism so that as a result of the automatic operation of the weighing mechanism substantially constant quantities of tobacco are always available at the point of bunch charge separation.

It is also an object of my invention to provide an improved bunch charge compression chamber and means associated therewith for weighing the quantity of tobacco remaining therein after a

5 bunch charge has been separated from the tobacco in the chamber and to feed such amounts of tobacco cyclically as will maintain in the compression chamber substantially uniform quantities of tobacco.

The invention also relates to an improved method for forming a succession of cigar bunch charges by forming a column of tobacco containing a quantity consisting of more than a single bunch charge, separating a bunch charge from the column, and feeding additional tobacco thereto in an amount necessary to reconstitute substantially the original quantity available for the formation of the next charge.

15 The invention also consists in the provision of an improved method for forming cigar bunch charges by confining a quantity of tobacco in an amount equal to or greater than a single bunch charge therefrom, removing a bunch charge, and adding a weighed quantity of tobacco thereto in amounts necessary to maintain the quantity of tobacco confined and available for bunch charge formation substantially constant.

20 An added object of the invention consists in an improved method of forming substantially uniform cigar bunches by providing a column of tobacco containing say one or more than a single bunch charge as a surplus after the separation of a measured charge therefrom, whereupon the surplus is tested to determine the amount of tobacco necessary to be added to the column in order to maintain available at all times for the formation of successive bunch charges a substantially constant column of tobacco.

25 With these and other objects not specifically mentioned in view, the invention consists in certain combinations and constructions which will be hereinafter fully described, and then set forth in the claims hereunto appended.

30 40 In the accompanying drawings which form a part of this specification, and in which like characters of reference indicate the same or like parts:

45 Figure 1 is a partial sectional side elevation showing a preferred form of the improved mechanism for controlling the feed of tobacco in accordance with quantities of tobacco remaining in the charge compression chamber after the removal of a bunch charge therefrom;

50 Figure 1a is an end elevation taken on the lines 1a—1a of Figure 1;

Figure 2 is a partial sectional elevation of a detail of Figure 1;

55 Figure 3 is a partial sectional side elevation of a modified form of the invention showing mechanism for weighing tobacco remaining in the charge compression chamber; and

60 Figure 4 is a side elevation of mechanism suitable for operating the charge compression chamber plunger and gate.

Referring to the drawings which show preferred forms of the invention selected for purposes of illustration, the machine consists of a bed plate 21 suitably mounting frame 18 which supports the mechanism. The filler tobacco, such as short filler, is deposited in a hopper H supported by a number of springs 10 fixed to a resiliently mounted vibratory base 12. In the illustrated embodiment base 12 is attached to resilient rubber cushions 14 fixed to cross bars 16 mounted on the hopper supporting frame 18 secured to the bed plate 21 of the machine. Vibratory base 12 is equipped with lugs 20 on which, by means of stud 22, is adjustably mounted a magnet supporting bracket 24 holding a magnet 26. An armature 28 is fastened to a lug 30 on hopper H. By increasing or decreasing the gap between the armature 28 and the magnet 26, the amplitude of the vibrator can be changed to any desirable degree thus making it possible to feed from the hopper any type of short filler tobacco with equally good results. The vibratory hopper, its vibrating mechanism, scale pan and tobacco flow stoppage element, preferably are constructed and operate much in the manner disclosed in Durning Patent No. 2,306,381 issued December 29, 1942.

As disclosed in the Durning patent above referred to, the bottom portion of the hopper H may be provided with a transverse step 32 which in effect separates the hopper into two sections, namely, a rear storage chamber 36 or portion in which a mass of tobacco is deposited and confined by a plurality of movable rakes 34 and a feeding part 38 provided with a distributing lip L over which a stream of tobacco issuing from the storage portion 36 is fed to the weighing mechanism 66.

The construction and operation of the rakes 34 is substantially the same as shown and described in the Durning patent. The tips of rakes 34 are located in front of step 32 and above the plane of portion 38 so that all tobacco passing from the confining portion 36 moves between the oscillatable rakes 34 which act to prevent any tobacco from trickling out or otherwise escaping from the confining chamber unless the rakes are moved transversely of the hopper. Rakes 34 are driven by means of vertical shaft 54 and suitable connections (not shown). Shaft 54 is supported by suitable bearings (not shown) through a conventional clutch (not shown) provided with a ratchet and pawl mechanism designated generally 108 operated by means of a solenoid 104 at proper times to initiate and stop the operation of shaft 54, all as shown and described in said Durning patent.

Tobacco as fed from the mass in the hopper H onto feeding trough portion 38 forms a thin layer T thereon. Due to the vibration imparted to the hopper H by magnet 26 and armature 28, layer T moves over section 38 and lip L and discharges into scale pan 66. As shown, the scale pan of the illustrated embodiment is located below lip L and includes a vertical scale plate 60. Each side edge of the scale plate 60 is provided with a lug 71 arranged to engage individual pivots 73 which are mounted in scale arms 69 both of which are fixed on a scale shaft 62. The latter is provided with bar or knife edges 75 resting in knife edge blocks 76 fastened by suitable means (not shown) to a U-shaped supporting bracket 74 mounted on a bracket 78 attached to the hopper supporting frame 18. The upper portion of scale plate 60 carries a pair of studs 64 pivotally mounting a scale receptacle forming together

with the plate 60, the scale pan into which the tobacco T fed from the hopper is delivered. The cross section of the scale pan, which is substantially wedge shaped, is of importance in aligning the pieces of short filler tobacco as they fall thereinto from the lip L.

Fastened to shaft 62 is an arm 68 carrying a threaded stud or scale beam 70 supporting a movable weight block 72. This block serves the purpose of balancing the scale pan as well as determining the amount of tobacco normally necessary to trip the scale pan. The position of block 72 on stud 70 can be adjusted, as desired, for controlling the feed of any normal weighed quantity of tobacco to scale pan 66. This quantity may contain enough tobacco to form a single bunch charge with a surplus over, or a plurality of charges, depending on the location of weight block 72 on stud 70.

As the layer of tobacco T formed by the vibrating hopper H is fed into the scale pan just described, the latter trips and swings downwardly when the desired amount is deposited therein. The downward movement of the scale pan causes a switch, such as a mercury switch 80 of conventional design, mounted on shaft 62 and connected in an electric circuit, to swing through an arc thereby breaking the circuit including the vibratory magnet 26 and causing the vibration of hopper H, movement of rakes 34, and feed of tobacco to the scale pan to stop. In order to prevent additional tobacco from discharging from the hopper into the scale pan after it has been tripped, a tobacco flow control plate 82 swings downwardly and closes the mouth of feed trough portion 38 as soon as the vibration of hopper H has ceased.

The plate 82 may be electrically operated and its action governed through a solenoid also controlled by switch 80. Control plate 82 is attached to a shaft 84 supported by a pair of brackets 86 mounted on bracket 74. Shaft 84 mounts a lever 88 which through rod 90 is connected to a lever 92 secured to a shaft 94 supported by a bearing lug 96 fixed to bracket 50. To shaft 94 is also fixed a bell crank lever 98, one end of which through a link 100, is connected with an armature 102 of a solenoid 104 mounted on housing 21. Solenoid 104 is energized and deenergized under the control of switch 80 thereby causing the movements of armature 102 to control the operation of plate 82. The other end of the bell crank lever 98 carries a lug 106 which is moved when solenoid 104 is energized to disconnect the pawl and ratchet connection 108 and interrupt the operation of the rakes 34.

Subsequent to the tripping of the scale pan the measured quantity of tobacco is discharged therefrom and transferred to the charge compression chamber designated generally C, in the manner described and set forth in the above referred to Durning patent. Since the construction of this mechanism is substantially the same as that shown in the referred to patent, only a brief description is deemed necessary in the present specification.

The guide chute consists of a pair of adjustably mounted stationary side plates 109. The front and rear walls of the chute consist of a movable magazine gate 110, and a movable guide plate 112, the former and latter moving in synchronism with each other. Plate 112 is fastened to a flange 114 mounted on a shaft 116 loosely supported in bearing lugs 115 of bracket 74. To shaft 116 is also fastened a lever 120 which

through a link 122 is connected to a lever 124 mounted on a shaft 126 supported by means of bearing brackets 128 attached to the magazine side rails (not shown) mounted on the magazine bottom plate 129 supported by frame 123 secured to the machine bed plate (not shown). Gate 110 is fastened to shaft 126 which is rocked by means of a lever 292 also mounted on shaft 126 (see Figure 4). Lever 292 is connected by means of an adjustable rod 294 to a lever 296 mounted on the shaft 118 supported by suitable bearings on frame 123. Shaft 118 carries a lever 119 which through an adjustable rod 298 is oscillated by a cam lever 300 loosely mounted on the lever supporting shaft 280. Cam lever 300 carries a cam follower 302 which when engaging with the curved portion 304 of a cam segment 306 causes the opening and closing of gate 110 as described heretofore. Cam segment 306 is secured to the rear side of cam 288 on shaft 280.

The charge compression chamber or magazine C is substantially the same in construction as that disclosed in said Durning patent and further detailed description thereof is deemed unnecessary except to state that it is formed by the bottom plate 129, a ledger plate 131, top plate 160, magazine gate 110, which oscillates on shaft 126, and the stationary rear and top plate 162. Top plates 160 and 162 are suitably supported by rails (not shown) fastened to bottom plate 129.

When the magazine C is ready for a charge and the scale pan holding the desired amount of tobacco is to be tripped, gate 110 swings upwardly in the direction indicated by the arrow A. During this movement the free end of gate 110 engages a trip finger 164 depending downwardly from plate 66 in the path of movement of gate 110 so that the engagement of gate 110 with finger 164 opens the scale pan and the contents discharge therefrom onto plate 112 for distribution in the chamber C upon plate 129. It will be seen that the construction and operation of gate 110 and plate 112 is such that these members form in effect a funnel to receive the tobacco discharged from the scale pan and as the gate 110 moves to closed position, plate 112 retreats and the tobacco is distributed in chamber C upon plate 129. When gate 110 has returned to its normal or closed position relative to the chamber C, reciprocating plunger 133 is moved forwardly (or to the right of Figure 1) to press part of the charge of tobacco in chamber C into a waiting charge transfer designated generally 224. The charge transfer 224 may be constructed and operated in the same manner as shown in said Durning patent.

In order to prevent the scale pan from swinging upwardly as soon as its charge is released, a locking device may be provided. Mounted in lug 74a of bracket 74 is a shaft 130 supporting a lever 150 provided with a locking lug 168. Lever 150 is connected by means of a link 154 to a flange 114 so that when plate 112 swings forwardly, lug 168 engages a cam follower 170 mounted on a lug 172 fixed to shaft 62 thereby locking the scale pan in down position and preventing reinstitution of vibratory motion of the hopper and additional feed therefrom until at the proper time the scale pan is raised by weight 72 to its upper or tobacco receiving position due to the reverse movement of plate 112 after a tobacco charge has been distributed in chamber C and lug 168 is moved out of locking engagement with cam 170.

Reciprocating plunger 133 which compresses the tobacco in the magazine C is mounted on a

plunger rod 174 slidably supported by supporting lug 176. The upper portion of lug 176 carries a turnable member 186 which on one end has secured thereto a hand knob 184, while the other end is provided with a threaded extension 187 carrying a lug 188 slidably supporting in its lower portion the plunger rod 174.

Lug 176 is equipped with a pair of studs 190 pivotally connected to a pair of brackets 192, 10 on an operating arm 194 pivoted to a pin 270 held by a lever 272 mounted on shaft 274 supported by bearing bracket 276 secured to the lower side of bed plate 21. Arm 194 is slidably supported by means of a guide lever 278 loosely mounted on a shaft 280 supported by suitable bearings in the machine frame. Guide lever 278 is provided with a cam lever 282 carrying a cam follower 284 engaging a cam track 286 in cam 288 on cam shaft 290 (Figure 4).

20 As described and disclosed in the above referred to Durning patent, while cam lever 282 imparts oscillating motion to guide lever 278 carrying the plunger operating arm 194, this motion of the lever is translated into a reciprocatory motion of arm 194 by the action of lever 272 connected to the arm by pin 270. For adjusting purposes the pin may be eccentrically mounted on a suitable bearing of lever 272 thereby providing means (not shown) for making fine adjustments. Plunger 30 133 is reciprocated by arm 194 through lug 176 and member 186 by means of lug 188 which during its forward stroke presses against a spring 216, encircling plunger rod 174, and extending between lug 188 and the rear face of plunger 133.

35 Spring 216 serves the purpose of compensating for any lost motion and permits arm 194 to keep its stroke free regardless of the amount of tobacco stored in the magazine thus avoiding jamming therein and assuring a more or less even amount of pressure of plunger 133 upon the tobacco column in the magazine C during each forward stroke of the plunger 133. The rearward stroke of plunger 133 is accomplished by means of lug 176 engaging the lower end 175 of bracket 214 which is fixed to rod 174. The arrangement of the bracket 214 with respect to the plunger 174 may assume various forms but for the purpose of illustrating one form thereof I show the same as being of conventional L shaped construction and 40 is connected directly to the member 175 on the free end of the plunger 174. The pressure of spring 216 upon plunger 133 can be varied to any desired degree by turning the hand knob 184 of member 186 thereby causing lug 188 to press or 45 release the spring 216 as the case may be. This valuable and desirable feature permits the use of scrap tobacco of any type and size which may require different density and pressure, and provides a satisfactory means for measuring the 50 quantity of tobacco in each charge.

In the mechanism described herein, it is evident that whenever a charge of tobacco in the charge transfer, designated generally 224, is separated from the column of tobacco in chamber C 55 by means of knife 220 which may be of the same construction and operation as that described and disclosed in the Durning patent above referred to, the plunger 133 is advanced to press the tobacco in the charge compression chamber C (as shown in Figure 1). Due to the timing of the mechanism which operates gate 110 to open the scale pan and allow a weighed quantity of tobacco to be served into the chamber C when the plunger 133 is retracted, vibration of the hopper H is 60 interrupted until the scale pan is returned by

weight 72 to tobacco receiving position relative to lip L of the hopper H and because of the counterclockwise movement of shaft 62, switch 80 is turned to complete a circuit through magnet 26 and solenoid 104 to reinstitute the vibration of hopper H and movement of rakes 34 to feed tobacco into the scale pan 66. The feeding operation takes place cyclically so that every time a charge is to be cut from the column of tobacco in the magazine C an additional quantity of tobacco is fed thereinto in the manner described hereinabove.

In order to insure that substantially uniform quantities of tobacco are present in the magazine C at all times, and hence make possible the formation of substantially uniform bunches, mechanism is provided for varying the amount of tobacco fed from hopper H into scale pan 66 in accordance with the surplus of tobacco remaining in the charge compression chamber C after each bunch charge in transfer 224 has been cut therefrom. In this way if a relatively small amount of tobacco, say enough to form one to three bunch charges, is present in charge compression chamber C, a greater quantity of tobacco is fed to scale pan 66 on the next feeding operation of the hopper H than would have been fed if, for instance, a relatively large quantity of tobacco, such as a quantity sufficient to form more than three bunch charges, remained as surplus in the chamber C prior to the next feeding operation of the hopper.

It will be seen, therefore, that an added object of my invention is to provide means for compensating automatically in the feed of tobacco to the chamber C in accordance with the surplus quantity remaining therein after the formation of a bunch charge by feeding such quantity in each cyclic operation of the feeding device such that a substantially constant quantity is present at all times in the chamber C for bunch charge formation.

In Figure 1 there is shown mechanism suitable for automatically feeding equal quantities, or varying the quantity of tobacco fed cyclically to the charge compression chamber to maintain therein a substantially constant quantity available for charge formation.

Pivotedly mounted on stud 200 on lug 68 is a weight 202 which extends downwardly between arms 203, 204 forming a part of lever 206 pivotally mounted on stud 203 supported in suitable bearing lug 79 of bracket 78. Lever 206 is also provided with an arm 210 extending downwardly into the path of movement of a threaded rod 212 carried by bracket 214 fixed to rod 174. While lever 206 may be loosely mounted on stud 208 for gravity return to its inoperative or neutral position after each cyclical operation, it is preferred to provide a pair of suitable friction washers 207 (Figure 2) which tend to hold said lever in its operative position until returned by positive means, described hereinafter. Threaded rod 212 is provided with a hand knob 218 by means of which it can be adjusted in its mount in order to control the throw of lever 206 which is engaged thereby during the displacement of bracket 214 by rod 174 in compressing tobacco in the charge compression chamber C by means of plunger 133, actuated by compression spring 216. A lock nut 220 may be employed to secure rod 212 in any adjusted position.

From the above it follows that whenever plunger 133 engages tobacco in the chamber C, if less than a predetermined normal surplus is present

therein, as determined by the position of weight 72 on stud 70, lever arm 210 of lever 206 will be rocked counterclockwise on its pivot 208 an amount corresponding with the quantity of tobacco remaining in the chamber C after the severance of a charge therefrom. This movement of lever 206 causes arm 204 to engage weight 202 and swing the same clockwise about its pivot 200 from a suitable predetermined neutral position, as viewed in Figure 1, thereby adding to the net weight of weight 72 an amount sufficient to cause an added quantity of tobacco to be fed to scale pan 66. In other words, the movement of weight 202 in the direction of arrow B causes the weight 202 to have a greater gravitational effect because of the movement of its center of gravity outward relative to its pivot on the lever arm constituted by lug 68 and rod 70. Weight 202 may be held fixed after each clockwise movement by any suitable means. In the illustrated embodiment a friction washer 201 (Figure 2) mounted on stud 200 between lug 68 and weight 202 performs satisfactorily. The amount of movement of lever 206, and hence the position of weight 202 vary cyclically in accordance with the position of plunger 133 at the end of each bunch charge separating operation. In order to return the weight 202 and lever 206 to their predetermined neutral positions upon completion of each weighing and feeding operation there is provided a rod 222, supported by bracket extension 214 on rod 174, which on its free end mounts a bracket 226 carrying an adjusting screw 228. Obviously weight 202 and lever 206 may be positioned substantially vertical, or depending on the setting of screws 212 and 228 at an angle. The screw 228, can be so adjusted that arm 203 of lever 206 will be swung into engagement with weight 202 as set screw 228 moves against arm 210 to displace weight 202 to its neutral position when plunger 133 is moved to its outermost limit in chamber C by arm 194 (to the left in Figure 1).

As shown in Figure 1, the electrical control may be somewhat similar to that shown in the above referred to Durning patent. An electrical circuit is provided in which are connected switch 80, relay R, solenoid 104 and magnet 26. When scale pan 66 is positioned to receive tobacco, switch 80 is in circuit closing position and relay 50 R is energized to effect the operation of solenoid 104 and magnet 26 thereby oscillating the rakes 34 and vibrating the hopper H. When the scale pan 66 trips, the circuit through switch 80 is broken, relay R is deenergized and the operation 55 of rakes and vibrator are interrupted.

In the modified form shown in Figure 3, tobacco is fed from vibratory hopper H which is provided with rakes 34 and vibrated in a manner similar to that shown in Figure 1, described hereinabove, to feed tobacco over trough portion 38 and lip L of hopper H into a chute 196 which directs tobacco into chamber C' between guide plates 209.

The charge compression chamber may be of the same general construction as that shown in said Durning patent. It is formed with the usual top plate 262 and a bottom plate 229 secured to a bracket member 231 forming a part of frame 123. The lower bottom plate is also formed of a substantially vertically movable plate or scale pan 233 suitably carried by bracket plate 234 which bracket plate may also mount ledger plate 233 with which coacts knife 220, constructed and arranged to operate in the same manner as set forth in the Durning patent, to separate the charge

in transfer 224 from the column of tobacco in chamber C'. Bracket 234 is supported for substantially vertical parallel movement by means of lever 236 pivoted at 238 on a stud carried in lug 240 on bracket 231. Lug 240 and bracket 234 are provided with equal length extensions 242, 244, respectively, having pivotally connected to their free ends a cross link 246, thereby providing for parallel motion of bracket 234 relative to plate 229 (as shown in Figure 3). Lever 236 is provided with a threaded rod 237 on which is mounted a weight 239 adjustable thereon along the threaded rod 237. The position of weight 239 on rod 237 determines the quantity of tobacco to be fed to chamber C'.

Chamber C' is provided with a gate 248 which is pivoted on a stud 250 adjacent top plate 262. The mechanism for operating gate 248 consists of a lever 252 fixed to gate 248 and connected by means of a rod 254 to lever 256 pivoted on shaft 118 in bracket 123. Lever 119 on shaft 118 is connected by means of adjustable rod 298 to lever 300 (Figure 4) loosely mounted on shaft 280 and rocked by means similar to that described in connection with the modification shown in Figures 1 and 2.

The plunger 133 which operates in chamber C' is of the same construction, as set forth above in connection with the modification shown in Figure 1 and is reciprocated by the mechanism shown in Figure 4. By this means any desired weight of tobacco can be set in order to control the amount of tobacco in the chamber C' so that regardless of the quantity remaining therein after a bunch charge has been cut therefrom, an additional quantity of tobacco is fed cyclically into the charge compression chamber C' after the plunger 133 has been retracted to its rear-most position, and gate 248 has been swung upwardly to allow tobacco to be fed over lip L of the hopper H and directed by chute 196 between side guide plates 209 into chamber C'. When tobacco is first fed from hopper H into the chamber C', the movable bottom plate or scale pan 232 is biased by weight 239 above the plane of bottom plate 229. Tobacco will be fed from the hopper H until plate 232 is in planar alignment with plate 229 and bracket 234 rests against stop plate 235 on bracket 231. A switch 243 mounted on lever 236 causes the circuit through the magnet 26 and solenoid 104 to be broken to stop the vibratory feed of tobacco to the charge compression chamber as soon as the desired weight of tobacco has been fed into the charge compression chamber C' and plate 232 has been returned to its final position (as shown in Figure 3). In the next cycle of operations, plunger 133 is moved into the charge compression chamber C' to compress the newly fed tobacco and the tobacco remaining in the chamber C' advances a measured charge into transfer 224 whereupon knife 220 is operated to sever the measured charge from the column in the chamber C' after which the plunger is retracted by means of arm 194. Plate 232 is again biased to weighing position, gate 248 is opened, additional tobacco is fed in an amount necessary to maintain the substantially uniform quantity of tobacco in the charge compression chamber C' according to the position of weight 239 and the quantity of tobacco remaining in the chamber on plate 232 or ledger plate 233. In the same manner all successive cycles of operation are carried out and more or less tobacco fed depending upon the weight of tobacco present in the chamber C'. It should be

noted that, if a quantity of tobacco remains on plate 232 when rod 174 is withdrawn by means of lug 176, the plate 232 will already be partially depressed when additional tobacco is fed from the hopper "H." As soon as the additional amount of tobacco, required to form a cigar bunch, has been deposited on the plate 232, the feeding is stopped in the manner described previously. This method of feeding results in greater uniformity of cigar bunches.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a cigar machine, mechanism for forming a succession of substantially uniform cigar bunch charges comprising, a tobacco feeding conveyor, a charge compression chamber, a plunger reciprocable in said chamber, a tobacco weighing device positioned to receive tobacco from said conveyor, means associated with said weighing device for causing said conveyor to feed a predetermined quantity of tobacco, auxiliary means associated with said weighing device for increasing the feeding effect of said first-named means, means on said plunger for operating said auxiliary means to control each amount of tobacco fed to said chamber in accordance with the surplus remaining therein after the formation of the previous bunch charge, and means for transferring tobacco from the weighing device to said chamber.
2. In a cigar machine, mechanism for forming a succession of substantially uniform cigar bunch charges comprising a tobacco feeding conveyor, a charge compression chamber, a plunger reciprocable in said chamber, a tobacco weighing mechanism positioned to receive tobacco from said conveyor, a control device also associated with said weighing mechanism for increasing the amount of tobacco fed to said weighing mechanism, said device comprising a movable weight arm, a forked lever, means mounting said lever with the forks thereof located on the opposite sides of said arm, means for reciprocating said plunger in said chamber, means on said plunger operative to engage said forked lever on the forward movement of said plunger to bias said weight arm from a neutral position and thereby increase the amount of tobacco fed by said conveyor to said weighing mechanism above a predetermined normal amount, and means for transferring tobacco from the weighing device to said chamber.
3. In a cigar machine, mechanism for forming a succession of substantially uniform cigar bunch charges comprising a tobacco feeding conveyor, a charge compression chamber, a plunger reciprocable in said chamber, a tobacco weighing mechanism positioned to receive tobacco from said conveyor, a control device also associated with said weighing mechanism for increasing the amount of tobacco fed to said weighing mechanism, said device comprising a pivoted weight arm, a forked lever, means mounting said lever with the forks thereof located on the opposite sides of said arm, means for reciprocating said plunger in said chamber, means on said plunger operative to engage said forked lever on the forward movement of said plunger to bias said weight arm from a neutral position

and thereby increase the amount of tobacco fed by said conveyor to said weighing mechanism above a predetermined normal amount, said last-named means including means for returning said weight arm to neutral position on each rearward movement of said plunger, and means for transferring tobacco from the weighing device to said chamber.

4. In a cigar machine, mechanism for forming a succession of substantially uniform cigar bunch charges comprising a tobacco feeding conveyor, a charge compression chamber, a plunger reciprocable in said chamber, a tobacco weighing mechanism positioned to receive tobacco from said conveyor, a control device also associated with said weighing mechanism for increasing the amount of tobacco fed to said weighing mechanism, said device comprising a pivoted weight arm, a forked lever, means mounting said lever with the forks thereof located on the opposite sides of said arm, means for reciprocating said plunger in said chamber, adjustable means associated with said plunger operative to engage said forked lever on the forward movement of said plunger to bias said weight arm from a neutral position and thereby increase the amount of tobacco fed by said conveyor to said weighing mechanism above the predetermined normal amount, said last-named means including adjustable means for returning said weight arm to neutral position on each related movement of said plunger, and means for transferring tobacco from the weighing device to said chamber.

5. In a cigar bunch charge forming machine, a charge compression chamber, a weighing device, said weighing device having a weighing plate constituting a part of said chamber, mechanism for feeding tobacco into said chamber onto said plate, and means carried by said device for controlling the operation of said mechanism.

6. In a cigar bunch forming machine for forming a succession of uniform cigar bunch charges comprising, a charge compression chamber, said chamber including a weighing device, mechanism for feeding tobacco into said chamber and onto said device, and means for incapacitating said feeding mechanism when a predetermined quantity of tobacco has been weighed by said device.

7. In a cigar bunch charge forming machine, a charge compression chamber, said chamber including a movable bottom weighing plate, mechanism for feeding tobacco into said chamber and onto said plate, and means for interrupting the operation of said feeding mechanism when a predetermined quantity of tobacco has been received on said plate.

8. In a cigar bunch charge forming machine, a charge compression chamber including an upper plate provided with a gate and a bottom plate provided with a weighing device, said device consisting of a vertically movable plate and associated weighing mechanism, means for opening and closing said gate, a feeding mechanism for feeding tobacco into said chamber whenever said gate is opened, and means under control of said weighing mechanism for controlling the operation of said feeding mechanism.

9. In a cigar machine, mechanism for forming a succession of substantially uniform bunch charges comprising a tobacco feeding conveyor, a charge compression chamber, said chamber having a top plate and a movable bottom plate portion spaced therefrom, weighing mechanism asso-

ciated with said bottom plate portion, a plunger reciprocable in said chamber, means for operating said plunger cyclically to compact tobacco within said chamber and to move out of compacting relation with any surplus tobacco which may remain in said chamber after a bunch charge has been separated therefrom, means for separating a bunch charge from said compacted tobacco, means for operating said conveyor to feed tobacco onto said plate portion, and control means carried by said weighing mechanism for incapacitating said conveyor when a predetermined quantity of tobacco has been delivered to said plate portion.

10. In a cigar bunch charge forming machine, a charge compression chamber comprising an upper wall provided with a gate, and a lower wall spaced therefrom provided with a movable tobacco receiving and weighing portion, means for opening and closing said gate, mechanism for feeding tobacco to said chamber for delivery thereto when said gate is open, and means under control of said weighing portion for incapacitating said feed when a predetermined quantity of tobacco has been fed by said feeding mechanism.

11. In a cigar bunch charge forming machine, a charge compression chamber, said chamber comprising an upper wall provided with a tobacco receiving opening, and a lower wall spaced therefrom provided with a movable weighing plate, supporting means mounting said plate for vertical movement relative to said lower wall, an adjustably mounted weight carried by said means, mechanism for feeding tobacco to said chamber for delivery through said opening onto said plate, and control means mounted on said supporting means for controlling the operation of said mechanism.

12. In a cigar bunch charge forming machine, a charge compression chamber, said chamber comprising an upper wall provided with a tobacco receiving opening, and a lower wall spaced therefrom provided with a weighing plate, movable supports mounting said plate for vertical movement relative to said lower wall, mechanism for feeding tobacco to said chamber for delivery through said opening onto said plate, and control means mounted on said supports for controlling the operation of said mechanism.

13. In a cigar machine, mechanism for forming a succession of substantially uniform cigar bunch charges comprising, a charge compression chamber for compacting tobacco therein, means for separating a bunch charge from the compacted tobacco in said chamber, feeding and weighing mechanism for forwarding a quantity of tobacco to said compression chamber substantially equal to the bunch charge removed each time, and control means operatively connected to said feeding and weighing mechanism for indicating the extent of variation in the quantity of tobacco remaining in said compression chamber after a bunch charge has been removed therefrom and for stopping the feed of tobacco to said compression chamber when substantially the same quantity of tobacco has been restored to said chamber as was removed therefrom to maintain the quantity of tobacco in said chamber substantially constant before each charge is separated therefrom.

14. In a cigar machine mechanism for forming a succession of substantially uniform cigar bunch charges comprising, a tobacco charge compacting chamber, feeding and weighing means for in-

termittently forwarding a controlled quantity of tobacco to said tobacco charge compacting chamber; a compactor for compacting the tobacco in said chamber; a cutter adapted to cut a bunch charge from said compacted tobacco; control means for indicating the extent of variation in the quantity of surplus tobacco remaining in said chamber after a bunch charge has been removed therefrom; and means interconnecting said control means and said feeding and weighing means to stop the operation of the latter means when a quantity of tobacco, substantially the same as the bunch charge removed, has been restored to the compacting chamber to maintain the amount of tobacco therein substantially constant.

15. The method of forming a succession of cigar bunch charges which consists in, forming a column of tobacco containing at least a single bunch charge and a surplus available for forming a subsequent charge, successively separating a bunch charge from said column, successively indicating the extent of variation in the amount of surplus tobacco remaining in said column after the separation of each charge, feeding tobacco to be incorporated with said column of tobacco after each separation of a bunch charge, collecting and weighing quantities of tobacco of substantially cigar bunch weight from the tobacco so fed, and varying automatically the quantity of tobacco so weighed after the separation of each bunch charge to compensate for differences in the quantity of surplus tobacco remaining in said column after a charge has been separated to thereby maintain the quantity of tobacco in said column substantially constant before the separation of each charge.

16. In a cigar machine, mechanism for forming a succession of substantially uniform cigar bunch charges comprising, a charge compression chamber, means for feeding tobacco to be delivered to said chamber to form a column sufficient for making at least one bunch charge, means for rendering said feeding means inactive, means for separating a bunch charge from said tobacco in said chamber, means for indicating the extent of variation in the quantity of any surplus tobacco remaining in said chamber after the separation of each bunch charge, means for successively reactivating said feeding means after a charge has been formed in order to feed additional tobacco in an amount necessary to maintain the quantity of tobacco in said chamber substantially constant before each charge is separated therefrom, means for weighing said tobacco as it is fed, said means for rendering said feeding means inactive being operatively connected to said indicating means for stopping the feed of said tobacco when a weight of tobacco varying in accordance with the quantity of surplus tobacco remaining in said chamber after the separation of a charge has been fed, and means for delivering said weighed quantity of tobacco to said chamber for association with said surplus.

17. In a cigar machine, a tobacco confining chamber, tobacco feeding mechanism, means for forming a measured bunch charge from said tobacco in said chamber, means for indicating the extent of variation in the amount of surplus tobacco remaining in said chamber after the formation of said charge, means for activating said mechanism for feeding tobacco to said chamber for addition to said surplus after the formation of a charge, weighing mechanism receiving tobacco as it is fed for delivery to said chamber, and means under control of said indicating means

for varying the capacity of said weighing mechanism in response to the indicated amount of surplus tobacco remaining in said chamber after the formation of a charge, whereby to maintain the quantity of tobacco in said chamber just prior to charge separation substantially constant at all times.

18. In a cigar machine bunch charge forming mechanism; a device for receiving portions of tobacco; feeding mechanism for conveying tobacco; weighing means between the feeding mechanism and said device for weighing tobacco fed by said feeding mechanism; means for compacting said tobacco in said device; means for forming bunch charges; means, associated with said compacting means, for indicating the extent of variation in the quantity of surplus tobacco which will remain in said device after the formation of a charge; and regulating means operatively connected to said indicating means for controlling the operation of said feeding mechanism to increase or decrease the amount of tobacco delivered by said feeding mechanism cyclically to said device to maintain the amount of tobacco substantially constant in said device prior to the formation of each charge.

19. In a cigar machine, a chamber for receiving portions of tobacco consisting of at least a single bunch charge and a surplus, tobacco feeding mechanism for feeding tobacco from a source of supply, a compacting mechanism in said chamber including a plunger, means for moving said plunger in said chamber for compacting said tobacco and forming bunch charges, means comprising a part of said compacting mechanism for indicating the quantity of tobacco present in said chamber to indicate the extent of variation in the surplus of tobacco which will remain in said chamber after the formation of a charge, weighing mechanism for receiving tobacco as it is fed by said feeding mechanism, and connections between said feeding mechanism and said weighing mechanism and between said measuring means and said weighing mechanism for incapacitating said feeding mechanism when an amount of tobacco necessary to maintain the quantity of tobacco present in said chamber and available for each charge to be formed substantially constant has been fed and weighed.

20. In a cigar bunch charge forming machine for a cigar machine, a charge compression chamber, including a weighing device constituting a part of said chamber, mechanism for feeding tobacco to said chamber, and means for incapacitating said mechanism when a predetermined quantity of tobacco weighed by said device has been delivered to said chamber.
